Application May 27, 1954, Serial No. 432,634

5 Claims. (Cl. 323—29)

This invention relates to voltage regulators utilizing an oscillator.

Diode devices are often employed to regulate the output voltage of a rectifier or other direct current voltage supply and may contain an ionizable gas. The degree of ionization varies with the voltage impressed across the diode so that when the diode is connected across the rectifier output terminals, any tendency of the voltage to increase results in an increased current flow through the diode. The diode may be connected in series with the internal rectifier impedance alone or with an external impedance so that the increased current flow results in the voltage across the diode being dropped to the desired value. An inherent feature of gas diodes is that a change of gas conditions is likely to occur as the diode ages and another is that the characteristic diode operating voltage varies with temperature and with the frequency of voltage variations or ripple frequency. In addition, the gaseous type regulator generally requires a starting voltage higher than the operating voltage of the source which it regulates.

It is an object of this invention to provide an improved voltage regulator.

It is a further object of this invention to provide a voltage regulator having a voltage-current characteristic which is stable over wide temperature ranges and with respect to a wide range of ripple frequencies.

It is a further object of this invention to provide an improved voltage regulator employing a diode discharge device having a readily adjustable voltage regulating level.

In accordance with this invention a magnetron oscillator is connected across the terminals of a voltage supply having a resistor in series therewith. Due to the low dynamic resistance of the magnetron oscillator when unloaded, it operates very effectively as a diode regulator. As is well known, the anode to cathode voltage required to start and sustain oscillations is determined by the oscillating frequency, the physical geometry of the magnetron device and the magnetic field strength. By varying the magnetic field strength or the frequency of oscillation, the magnetron operating voltage and hence the regulating level is readily varied over a wide range of values.

The novel features which are believed to be characteristic of the invention are set forth with particularity in the appended claims. The invention itself, however, together with further objects and advantages thereof can best be understood by reference to the following description taken in connection with the accompanying drawings in which Figure 1 represents a basic regulating circuit incorporating our invention. Figure 2 is a curve of the variation of direct current voltage as a function of direct current for a traveling wave magnetron; Figure 3 is a perspective view of a type of magnetron which may be employed in the circuit of Figure 1; Figure 4 illustrates a differential connection for magnetron voltage regulators; Figure 5 illustrates a parallel connection for magnetron voltage regulators; Figure 6 illustrates a cascade connection for magnetron voltage regulators; and Figure 7 illus-

trates a modified magnetron voltage regulator circuit having feedback means for varying the magnetron magnetic field.

Figure 1 shows terminals 1 and 2 connected to direct current voltage source 3. Source 3 may be a rectifier subject to ripple or other voltage fluctuations. A regulating or dropping resistor 4 is shown inserted in series between source 3 and one of the terminals, and a resistive load 5 is connected across terminals 1 and 2 so that the source voltage is divided between resistor 4 and load 5. The resistor 4 may also be considered to include the internal resistance of the voltage source. The regulator 6 is a traveling wave magnetron having an elongated thermionic cathode 7 connected to the negative terminal 1 and a split anode 8 connected to the positive terminal 2. For simplicity of illustration, the magnetron anode 8 is semi-schematically illustrated as having two segments which surround cathode 7 to form a cylindrical space charge chamber. An unloaded resonant output circuit 9 is connected between the anode segments. Solenoid 10 provides an axially directed magnetic field through the space charge chamber. The terminals of solenoid 10 are connected to an adjustable direct current voltage source 11. A suitable source of heater current 12 is connected to cathode 7.

The magnetron is operated as a conventional traveling wave type with the direct current radial electric field and the axial magnetic field in the space charge chamber acting upon the electronic space charge so that it assumes an average angular velocity about the cathode. When the electrons traversing a gap between adjacent anode segments are in phase with the fringing alternating electric field between the segments they reinforce the oscillations established by the initial excitation of the tuned circuit 9 by giving up part of their kinetic energy to the alternating electric field. Upon losing some of their energy the electrons move toward the anode to regain energy, being eventually collected there. In this way the space charge envelope is caused to assume a spoke-shaped form, each spoke corresponding to a region of in-phase electrons having an average angular velocity synchronous with the high frequency electric field of the anode assembly. This is customarily termed π mode excitation.

An increase in the applied radial electric field tends to increase the average angular velocity above synchronism, but the resonant output circuit, being unloaded, substantially fixes the operating frequency so that once the oscillation threshold is reached, a further increase in the applied voltage between the anode and cathode results only in a larger electron direct current being collected at the anode.

A typical characteristic curve of direct current voltage as a function of direct current for a traveling wave type magnetron is shown in Figure 2 as substantially flat for current values above the knee of the operating curve. The voltage drop across the magnetron is substantially constant over a wide range of current through the magnetron so that when operating above the knee of the curve the dynamic resistance of the magnetron diode may be considered to be very low. The dynamic resistance of a device may be defined as the quotient of an incremental change in voltage across the device divided by the resulting incremental change in current through the device and may also be defined by the expression

$$\text{Dynamic resistance} = \frac{\Delta E}{\Delta I}$$

The magnetron is designed, as is conventional, so as not to be emission limited. Since the oscillation threshold occurs at the knee of the curve and is dependent upon the ratio of the radial electric field to the axial

magnetic field, the magnetic field density may be adjusted by varying the voltage of the source 11 to adjust the magnetron operating level. The operating voltage may also be varied by changing the resonant frequency of the output circuit 9. In order to maintain a low value of dynamic resistance, the output circuit 9 is tuned and broadening of its tuning is prevented by maintaining the output circuit unloaded.

It may be seen, by referring to Figure 1, that when the voltage of the source 3 tends to rise to a value above the knee of the curve of Figure 2, the magnetron current increases very rapidly, thereby increasing the current through the resistor 4. The increased current through resistor 4 increases the voltage drop across resistor 4 and tends to maintain a nearly constant voltage across terminals 1 and 2. Since the magnetron oscillation frequency is in the order of megacycles, the magnetron dynamic resistance remains essentially constant over a frequency range from zero cycles per second up to frequencies in the order of megacycles per second. At high frequencies the sharpness of tuning of the output circuit no longer will allow the anode current to build up in the same ratio to the anode voltage as it does at lower ripple frequencies so that the curve of Figure 2 is no longer substantially flat. In this respect, the magnetron voltage regulator is superior to the conventional gas diode in which the dynamic resistance usually increases rapidly to a very high value at only a few hundred cycles per second. Therefore, no bypass arrangements are necessary to accommodate high frequency voltage source changes.

The magnetron reaches its operating voltage smoothly without requiring a breakdown from a higher voltage. The long time stability of the magnetron regulator is also superior since, as a high vacuum device, it is not subject to changes of gas conditions as may occur in gaseous regulators or is it sensitive to temperature variations. Furthermore, the regulating level can easily be adjusted over a wide range by changing the density of the axial magnetic field.

Figure 3 shows a miniature type low cost magnetron which may be suitably employed as the magnetron 6 of Figure 1. This magnetron is of the interdigital type having two interleaved sets of anode vanes which are connected by an inductive metal loop. The loop and any vane-to-vane capacity form an internal tank circuit. For details of constructional features of small low cost magnetrons of this general type, reference is made to U. S. Patent 2,617,956, issued November 11, 1952 to L. U. Hamvas and assigned to the assignee of the present invention.

The magnetron of Figure 3 has a tubular glass envelope 13 which includes a disk-like base portion 14 through which a plurality of relatively stiff direct current lead-in connectors are sealed in a mutually spaced and insulated relation, the connectors being preferably arranged to cooperate with a conventional tube socket. An exhaust and seal-off tubulation 15 may conveniently be located in the upper end of envelope 13 as shown.

The magnetron anode structure includes two annular metal disks or rings 16 and 17 spaced in parallel planes along a common axis transverse with the lengthwise axis of the tubular envelope. Each of the annular disks or rings has a similar plurality of digital projections which are bent to extend in an axial direction towards the opening in the opposite anode ring. In the example shown, the anode ring 16 has a set of four such equally spaced projections 19 which are interleaved with but spaced from the corresponding set of four projections 18 integral with the other anode ring 17. These projections are the anode vanes or segments and define a substantially cylindrical space charge chamber between their inner surfaces. An insulating spacer disk 20, constructed of a suitable insulating material such as mica, is secured to the outer surface of the anode ring 16, preferably by

tabs, and is apertured to receive and support the free ends of the vanes 18 extending from the opposite anode ring 17. A similar disk 21 is secured to the anode ring 17 and is similarly apertured to receive and support the ends of the anode segments 19. This construction permits the desired equal spacings between the adjacent anode segments to be maintained.

A cylindrical cathode sleeve 22 is axially positioned in insulating relation with the anode segments 18 and 19 by central openings in the spacer disks 20 and 21 through which the cathode ends extend. The cathode sleeve, which is suitably made of nickel, is coated with a thermionically emissive substance, such as barium oxide, which emits electrons when heated by element 23 positioned within the cathode sleeve to provide the magnetron space charge. The right-hand end of the cathode sleeve is preferably closed to reduce heat losses by radiation and is conductively supported by a lead-in conductor 24. The ends of the heater are brought out through the open left-hand end of the cathode sleeve and are suitably welded to the internal ends of lead-in conductors 25 and 26.

The resonant output circuit for the magnetron is provided by a conductive loop 27 having its ends attached to the anode end rings 16 and 17. In the device of Figure 3, this loop is positioned within the envelope and made of a relatively stiff conductor extending toward the base of the device. A lead-in conductor 28 is welded or otherwise firmly secured to the midpoint of loop 27 to support the electrode assembly and provide a direct current anode connection. No high frequency anode coupling means or terminals are required since the output circuit is preferably unloaded to keep the dynamic resistance between the anode and cathode at a minimum value. It is to be understood that while the loop 27 has a small inductance, which is all that is needed for the high operating frequencies for which magnetrons of this type are customarily designed, the output circuit may be provided with additional turns for greater inductance as may be desired for lower frequency operation or with means for varying the inductance.

The device is conventionally evacuated and sealed. An inductive loop including a strip 29 is supported from one of the lead-in conductors. A suitable getter such as barium is placed on strip 29. After the final evacuation and sealing of the envelope, the loop may be excited by induced high frequency energy to heat and vaporize the getter material and thus absorb any residual gases remaining in the envelope.

Also shown in Figure 3 is an annular permanent magnet 30 surrounding the envelope 13, the magnet being notched and magnetized to define the dissimilar poles facing opposite ends of the space charge chamber. Electromagnetic means may, of course, be alternatively or additionally provided for establishing the axial magnetic field in the space charge chamber.

It is to be understood that various other types of magnetron constructions may be employed in arrangements embodying our invention. For example, a traveling wave magnetron having an anode block with cavity resonators incorporated therein may be employed. The hole and slot type of cavity resonator is a typical arrangement in this type of construction, the anode segments defined between adjacent slots being interconnected by the material of the anode block; therefore, no output coupling means is necessary if a cavity resonator type of magnetron is utilized as a voltage regulator.

While magnetrons may readily be designed for operation at relatively high direct current voltages, it may be more convenient where a low voltage is to be regulated or where the size of available magnetrons does not permit operation at a desired low voltage, to utilize two differentially connected magnetrons. Figure 4 shows a first dropping resistor 4 and magnetron 6, series connected, as in Figure 1, across the output terminals of the

voltage source 3 and a second dropping resistor 4' and a second magnetron 6' connected across the output terminals of source 3. The magnetrons have different operating characteristics or are provided with different magnetic field strengths in their space charge chambers so that they have operating voltages differing by the desired output voltage.

The load circuit is connected to the respective output circuits of the two magnetrons for low voltage operation. It may also be seen that by varying the operating voltage of one or both magnetrons, the differential output voltage may not only be reduced to zero but its polarity may be reversed as may be desired for certain applications.

It is to be understood that two or more magnetrons may be operated in parallel so that their combined dynamic impedance or resistance is decreased, thus providing a curve of voltage as a function of current having a lesser slope than the slope of the curve shown in Figure 2. Figure 5 illustrates, by way of example, a circuit arrangement utilizing parallel operated magnetrons. Likewise, a number of magnetron regulators may be operated in cascade, as illustrated in Figure 6, with each cascade unit having its own voltage dropping resistor 4 and 4' respectively. In Figures 5 and 6, components which are similar to those in Figures 1 and 4 are identified by the same reference numerals.

The magnetron regulator may be made more sensitive to changes in the voltage source and to changes in the load by passing the anode current through a solenoid so positioned that it decreases the axial magnetic field in the magnetron as indicated in the circuit of Figure 7. Here, as in Figure 1, a magnetron 6 is connected with its output circuit 9 through a resistor 4 to the terminals of a voltage source 3 to be regulated. The magnetic field provided by a solenoid 10 is adjusted to provide the desired normal magnetron operating voltage. A first auxiliary solenoid winding 31, which is positioned to produce a magnetic field aligned with that produced by the solenoid 10 is connected in series between the magnetron 6 and the voltage source 3. The solenoid 31 is connected so as to decrease the total magnetic field when the anode current increases. The solenoid 31 is connected between the anode output circuit 9 and the dropping resistor 4. A second solenoid 32, also positioned to oppose the flux of the solenoid 10, is connected in series with the load 5, the load circuit being connected across the magnetron but not including the solenoid 31.

Solenoid 31 has the effect of decreasing the slope of the characteristic curve of Figure 2 so that the operating voltage is very little higher at high current values than the voltage at the knee of the curve. Thus, when the voltage of the source 3 increases, as may be caused by a voltage ripple, the magnetron draws more current and increases the voltage drop across the resistor 4. At this high value of current the voltage across the magnetron tends to increase. The increased current through the solenoid 31 results in a decrease in the total magnetic field through the magnetron space charge chamber. Accordingly, a lesser electric field is required for oscillation, and the voltage across the magnetron tends to decrease so that the over-all curve of voltage as a function of current tends to be flatter for current values above the knee of the curve. In a like manner, a change in the load current has a similar effect in that an increase in load current in solenoid 32 lowers the magnetic field and results in a flatter over-all curve of voltage as a function of current.

From the foregoing, it is to be seen that in accordance with our invention a traveling wave type magnetron is very effectively employed as a voltage regulator device in various voltage regulating circuits. It operates very effectively to regulate voltages over a wide frequency range of voltage fluctuations and the regulating characteristics are substantially independent of temperature. The

magnetic field strength can readily be adjusted to change the operating voltage to any desired value over a wide range. The changes in the anode current drawn by the magnetron as a regulator cause very little change in the operating voltage, particularly so long as the magnetron output circuit is unloaded and the radio frequency power generated by the magnetron is not externally dissipated.

While the present invention has been described by reference to particular embodiments thereof, it will be understood that numerous modifications may be made by those skilled in the art without departing from the invention.

What we claim as new and desire to secure by Letters Patent of the United States is:

1. A voltage regulator comprising a source of voltage to be regulated, a magnetron discharge device having a cathode and an anode electrode, a resonant output system including said anode electrode, means for producing a magnetic field along the space between said anode and cathode, an impedance, means coupling said cathode and said anode respectively through said impedance to said voltage source to produce an electric field between said cathode and said anode and operate said magnetron at the resonant frequency of said output system whereby the low dynamic resistance of the magnetron causes a large current change therethrough corresponding to relatively small voltage changes in said source to obtain a regulated voltage across said discharge device having a magnitude determined by the strength of said magnetic field and the resonant frequency of said output system.
2. A voltage regulator comprising a source of voltage to be regulated, a magnetron discharge device having a cathode and an anode, an unloaded resonant output system including said anode, means for producing a magnetic field along the space between the cathode and anode, an impedance, means coupling said cathode and said anode respectively through said impedance to said voltage source to provide an electric field between said cathode and said anode and operate said magnetron at the resonant frequency of said output system whereby the low dynamic resistance of the unloaded oscillating magnetron causes a large current change therethrough corresponding to relatively small voltage changes in said source to obtain a regulated voltage across said discharge device having a magnitude determined by the strength of said magnetic field and the resonant frequency of said output system.
3. A voltage regulator comprising a source of direct current voltage to be regulated, a magnetron discharge device having a cathode and an anode, an unloaded resonant output system including said anode, means for producing a magnetic field along the space between the cathode and anode, an impedance, means coupling said cathode and said anode respectively through said impedance to said voltage source to provide an electric field between said cathode and said anode and operate said magnetron at the resonant frequency of said output system whereby the low dynamic resistance of the unloaded oscillating magnetron causes a large direct current change therethrough corresponding to relatively small voltage changes in said source to obtain a regulated direct current voltage across said discharge device.
4. Means for regulating the voltage between a pair of terminals comprising a first magnetron oscillator including an anode, a cathode, and a first unloaded resonant output circuit including said anode, a voltage dropping impedance means for coupling a source of direct current energy to be regulated across said first magnetron oscillator through a voltage dropping impedance to produce an electric field between said cathode and said anode and operate said magnetron oscillator at the resonant frequency of said first output circuit, a second magnetron oscillator including an anode, a cathode and a second unloaded resonant output circuit including said anode, a second voltage dropping impedance, and means for coupling said second magnetron across said first mag-

netron oscillator through said second voltage dropping impedance to obtain a regulated output voltage across said second magnetron oscillator.

5. Means for regulating the voltage between a pair of terminals comprising, a first magnetron oscillator including an anode, a cathode and a resonant output circuit including said anode, means for producing a magnetic field along the space between said anode and cathode, an impedance, means for coupling a source of energy to be regulated to said first magnetron through said impedance to produce an electric field between said cathode and said anode and operate said magnetron at the resonant frequency of said output circuit, a second mag-

netron oscillator including an anode, a cathode and a resonant output circuit, a second impedance, said second magnetron oscillator being coupled across said first magnetron oscillator through a second impedance to obtain a regulated voltage output.
